UNITED STATES PATENT OFFICE.

HENRY R. LADD, OF ORWELL, OHIO.

COMBINED FIRE-ESCAPE AND BED-BOTTOM.

SPECIFICATION forming part of Letters Patent No. 242,780, dated June 14, 1881.

Application filed May 7, 1881. (No model.)

To all whom it may concern:

Be it known that I, HENRY R. LADD, a citizen of the United States, residing at Orwell, in the county of Ashtabula and State of Ohio, have invented certain new and useful Improvements in Combined Spring-Bed Bottom and Fire-Escape; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention relates to that class of spring-bed bottoms which are composed of parallel sections or frames, flexibly connected together so as to be readily converted into a fire-escape ladder, and having the springs which 20 support the bedding adapted to serve as fenders to hold the ladder from the wall of a building.

25 The object of the invention is to simplify the construction of the frames which comprise the bed-bottom and escape-ladder, and to connect the same in such a manner that they can be easily and conveniently folded alongside of each other when used as a bed-bottom, and caused to assume a straight position in relation to each other when thrown out of a window, so as to form a regular ladder, having the adjoining ends of the various sections close together.

30 To these ends the invention consists in the construction and combination of parts, which 35 will be hereinafter more fully described, and then set forth in the claims.

In the accompanying drawings, Figure 1 is a plan or top view, showing the parts in position to form a bed-bottom, several sets of springs 40 being uncovered to exhibit the parts more clearly. Fig. 2 is a bottom view, showing the arrangement of the cords which serve to connect the various sections or frames. Fig. 3 is an 45 elevation, illustrating the parts in position to form a flexible escape-ladder. Fig. 4 is a detail sectional view, showing the arrangement of a supplementary ladder-section below a section of the spring-bed.

50 The letter A designates parallel frames or sections, consisting each of two side bars, a, and connecting slats or rounds b. These frames

A extend across the bedstead-frame B, and when folded alongside of each other, as shown in Figs. 1 and 2, have the ends of the side bars seated in notches made in the side rails of the bedstead. The side bars, a, and slats b constitute the frames which make up the bed-bottom and flexible escape-ladder. The helical springs C, upon which the bedding is supported, 55 are secured to the slats b in any approved manner. The various sets of springs, or the sets belonging to each frame or section, are covered with a strip of canvas or other textile material, D, a strip for each section, so as to maintain said springs in their proper relative positions and guard against their becoming twisted or displaced.

The sections or frames comprising the bed-bottom are connected together by means of 70 cords, straps, or chains E and F, which are generally continuous or made to extend throughout the entire length of the various sections, so as to avoid the use of more than two cords. These cords are passed through suitable holes made 75 in the side bars of the frames or sections, or through eyes attached thereto, and they are so arranged in relation to the frames as to permit the latter to be conveniently folded alongside of each other for forming a bed-bottom.

80 The manner of disposing or arranging the cords may be described, as follows, viz: The cord E, connecting the various frames at one side thereof, is first knotted or secured to the head section of the bed-bottom or top section 85 of the ladder, and from the first point of attachment it passes along the side bar of the frame and is again attached at a short distance from the center of said frame. From this second point of attachment the cord runs 90 beyond the second or next adjacent section, and is attached at a point a short distance above the center of the side bar of said second section. The cord then runs to the bottom of said second section and is knotted thereat, 95 and is then passed to the third section or frame and secured to the upper end of the same. A short link or flexible connecting portion is thus formed, by the cord E, between the second and third sections, while a longer link or connecting portion is formed between the second and first sections. The cord F is attached to the top of the first section or frame in the same manner as the cord E, and runs along the side

bar of said frame to its lower end, where it is secured. It then passes beyond said first frame and is again secured to the top of the second frame, so as to leave a short link or connecting portion between these two frames. The cord F runs along the second frame, and is attached at some distance above the bottom thereof, and from thence it extends to a point a suitable distance below the top of the third 5 or next adjacent frame, so as to form a long link or flexible portion in the cord F between the second and third frames.

It will readily be apparent that, by connecting the various frames or sections in the manner shown, or by having short or long links or flexible portions in the cords alternately at opposite sides of said frames, the latter can be expeditiously and conveniently folded alongside of each other so as to constitute a bed-bottom. When a fire-escape or flexible ladder is required in cases of fire, or otherwise, the bed-bottom is taken up and passed or thrown out of a window. The various frames or sections will then assume their proper positions or 10 be in exact line with each other, with the springs and canvas covers toward the wall of the building. The cords E F, which serve to connect the frames, will, by reason of their peculiar attachment, prevent said frames from remaining in the wrong position, even if the cords should be twisted when the ladder is passed out of the window. On the contrary, the cords will have a tendency to cause the frames to turn properly until they are all in the required 15 positions, so as to form an unbroken or regular ladder. The top section of the ladder, or foot or other section of the bed-bottom, is connected with the bedstead by extending the cords E F and securing the same to the bed- 20 stead. These extensions of the cords E F or other cords attached thereto or to the ladder carry a transverse roller, G, having end disks or flanges, H. The roller or spool rests upon the window-sill and serves to form a space between said sill and roller to permit the introduction of the hand in passing onto the ladder. 25

It has already been stated that the springs of the bed-bottom serve to hold the ladder from the wall of the building. This feature has 30 already been suggested in a combined bed-bottom and fire-escape of a known construction.

In my invention the cross-slats which form the rounds of the ladder also serve to support the springs, and, being attached to the upper 35 surface of the side bars, these slats are so located as to permit the person descending the ladder to move between the side bars of the same. In this manner greater security is attained, and, moreover, should any of the 40 rounds or cross-bars break or slip, the springs

and canvas cover attached thereto will generally obviate accidents by serving as a medium for preventing a too sudden or entire separation of said rounds or cross-bars. The springs arranged upon the cross-bars or rounds 45 can also be set closer together or at more regular intervals apart than if applied to the side bars.

The canvas covers are cut out at their ends, so as to permit the hand and foot to be introduced in making the descent on the ladder. 50

It may sometimes be necessary to provide a ladder longer than can be constructed of the spring-sections comprising the bed-bottom. To this end I attach one or more ladder-sections, I, to the section of the bed-bottom constituting the lowest ladder-section. Cords or flexible links are used to connect these supplementary ladder-sections, and when not in use they are stowed away under the spring-bearing section by making the notches in the bedstead rails sufficiently deep. Pins i on said supplementary sections serve to hold them away from the wall of a building. 55

Having thus described my invention, what 85 I claim as new, and desire to secure by Letters Patent, is—

1. A combined bed-bottom and fire-escape composed of parallel sections or frames, flexibly connected at their ends, and constructed 90 of side bars, cross-strips applied to the upper side of said bars, helical springs secured to said cross-strips, and canvas covers secured to the springs and frames, as and for the purpose set forth. 95

2. In a combined bed-bottom and fire-escape, the combination of the connecting-cords E F with the ladder and bed-bottom sections or frames, said cords being attached to said frames to form short and long connecting-links between each adjacent pair of frames, as herein set forth. 100

3. The combination of the roller having end flanges with the top section of the ladder, and the attaching-cords leading therefrom, as and for the purpose set forth. 105

4. In a combined bed-bottom and fire-escape, the combination of supplementary ladder-sections, provided with projecting pins, with spring-bearing sections flexibly connected thereto, and a bedstead having notches for the ends of said supplementary sections, as and for the purpose set forth. 110

In testimony whereof I affix my signature in presence of two witnesses.

HENRY R. LADD.
